HUB CAP

Millard Fillmore Harty, Jr., Bloomfield Hills, Mich., assignor to Motor Wheel Corporation, Lansing, Mich., a corporation of Ohio

Filed Jan. 14, 1970, Ser. No. 20,917

Term of patent 14 years

Int. Cl. D12—14

U.S. Cl. D14—30

FIG. 2

FIG. 3

FIG. 1 is a front elevational view showing the outboard face of a hub cap, showing my new design.

FIG. 2 is a vertical sectional view taken on the line 2—2 of FIG. 1.

FIG. 3 is a perspective view of the hub cap shown in FIG. 1.

I claim:

The ornamental design for a hub cap, substantially as shown.
